UNITED STATES PATENT OFFICE

EDWIN C. KUBLER, OF ST. ALBANS, NEW YORK, ASSIGNOR TO AMERICAN LEAD PENCIL COMPANY, OF NEW YORK, N. Y., A CORPORATION OF NEW YORK

DESIGN FOR A DISPLAY STAND

Application filed February 12, 1931. Serial No. 38,629. Term of patent 3½ years.

To all whom it may concern:

Be it known that I, EDWIN C. KUBLER, a citizen of the United States and a resident of St. Albans, Long Island, New York, United States of America, whose post-office address is 194-31 114th Road, St. Albans, Long Island, New York, have invented a new, original, and ornamental Design for a Display Stand, of which the following is a specification, reference being had to the accompanying drawing, forming part thereof.

I claim:

The ornamental design for a display stand, as shown.

Dated at New York, N. Y., this 4th day of February, 1931.

EDWIN C. KUBLER.
